DESIGN FOR A LIPSTICK ADVERTISING DEVICE

Florence N. Lewis, New York, N. Y.

Application December 4, 1941, Serial No. 104,463

Term of patent 3½ years

To all whom it may concern:

Be it known that I, Florence N. Lewis, a citizen of the United States of America, residing in New York city, county of New York, and State of New York, have invented a new, original, and ornamental Design for a Lipstick Advertising Device, of which the following is a specification, reference being had to the accompanying drawing, forming part thereof, wherein advertising device showing my new design, and Figure 2 is a side elevational view thereof.

The characteristic feature of my design resides in the variety of ends shown on the extended arms.

I claim:

The ornamental design for a lipstick advertising device, substantially as shown, and described.

FLORENCE N. LEWIS.
